(57) **CLAIM**

We claim the ornamental design for a movement measurement device housing, as shown and described.

DESCRIPTION

FIG. 1 is a front isometric view of an embodiment of a movement measurement device housing.

FIG. 2 is a rear isometric view of the movement measurement device housing of FIG. 1.

FIG. 3 is a front elevation view of the movement measurement device housing of FIG. 1.

FIG. 4 is a rear elevation view of the movement measurement device housing of FIG. 1.

FIG. 5 is a right side elevation view of the movement measurement device housing of FIG. 1.

FIG. 6 is a left side elevation view of the movement measurement device housing of FIG. 1.

FIG. 7 is a top plan view of the movement measurement device housing of FIG. 1; and,

FIG. 8 is a bottom plan view of the movement measurement device housing of FIG. 1.

Portions shown in evenly spaced broken lines depict environmental structures that form no part of the claim. Portions shown in dot-dash lines depict an unclaimed boundary between claimed and unclaimed portions of the present design.

Any combination of the illustrated features may be claimed in this application or a continuing application claiming priority to this application by converting any of the solid lines to broken lines, any of the broken lines to solid lines, or any combination thereof.

1 Claim, 7 Drawing Sheets
